COMBINED COSMETIC AND MAKE-UP CASE

Matthew J. Rothman, New York, N.Y.
(140-35 Beech Ave., Flushing, N.Y. 11355)

Filed Apr. 3, 1967, Ser. No. 6,524

Term of patent 7 years

(Cl. D86—10)

FIG. 1

FIG. 2

FIG. 6

FIG. 5

FIG. 4

FIG. 3

FIG. 1 is a front perspective view of a combined cosmetic and make-up case showing my new design in fully open condition;

FIG. 2 is a top plan view in closed condition;

FIG. 3 is a left side elevational view thereof;

FIG. 4 is a front elevational view thereof;

FIG. 5 is a right side elevational view thereof;

FIG. 6 is a rear elevational view thereof.

The essential features of the design are shown in full lines.

I claim:

The ornamental design for a combined cosmetic and make-up case, substantially as shown and described.
